Walter Ringel

UNITED STATES PATENT OFFICE.

CLESTIN RINGEL, OF SAN FRANCISCO, CALIFORNIA.

GOLD-WASHER.

Specification of Letters Patent No. 26,524, dated December 20, 1859.

To all whom it may concern:

Be it known that I, CLESTIN RINGEL, of the city and county of San Francisco, State of California, have invented a new Machine 5 for Working Gold-Bearing Deposits, the purpose of which is to set the gold free from clay, cement, cemented conglomerate, lava, decomposed slates and granites, or any matter in which it is not inclosed by the force 10 of chemical affinity; and I do hereby declare that the following is a full and exact description thereof.

The nature of my invention consists in the following:

15 First, I construct and use the inner part of a water wheel as a receiver of the gold containing clay, cement etc.

Second, I reduce the gold containing clay, cement, etc. into such a state of division by 20 the rotation of the wheel and the friction with the inner parts of the wheel, that all the clay, cement etc. which may inclose particles of gold go off as mud and leave nothing but the gold and the clean pieces of 25 rocks.

Third, I combine, consequently the motive power of a water wheel with a separating or reducing machine in one apparatus.

Fourth, I use the same water, which at 30 present is only used for sluicing, for the following purposes: A, for the transportation of the gold bearing clay, cement etc. to the wheel. B, for the motion of the wheel. C, for the isolation of the particles of gold 35 from the clay, cement, etc. by reducing them to mud sand and clean pieces of rocks in the inner part of the wheel. D, for the extraction of the gold from the reduced parts, outside of the wheel.

40 To enable others to make and use my invention I will proceed and describe its construction and operation.

Construction.—I construct a waterwheel of 8 feet in diameter, more or less, and about 45 2½ feet wide with two rims: R, R'. I place the arms for the two rims, A, A', in the inner part of the wheel so that there is 6 inches or more of space between them and 6 inches or more from each arm to the side of 50 the wheel. I cover both sides of the wheel near the periphery with sieves, or perforations in wood, sheet or cast metal; or I cover both sides of the wheel with planks, sheet or cast metal, and leave a concentric opening of 55 one quarter of an inch more or less, through which the reduced matter can pass out of

the wheel; or I use the concentric opening with sieves or perforations in every part of the wheel, where a discharge of the reduced or isolated particles is desired. The supports of the buckets are fastened from the inside on the rims, because the pressure of the charge in the wheel is outward and the rims and arms have to bear the resistance. The support of every bucket has a few small 60 holes or openings, so as to let an inch or more of water pass into the inner part of the wheel. The supports of the buckets form two inclined planes from the middle to the sides of the wheel for the purpose of giving 65 to the particles of gold and to the reduced matter more facility to slide out on each side of the wheel. The whole inner surface of the wheel which is formed by the two inclined planes is covered with sieves or perforations in metal. Only one place, occupied 70 by a door on the periphery is uncovered. The door is opened, without stopping the wheel by a knob with a hammer on a shover. After a few turns the rocks are 75 discharged and by replacing the shover it is closed. In the model one quarter of the inner surface is covered with perforated metal. Each point of it is equidistant from the axis and has consequently no inclination 80 to either side of the wheel. The arms of the wheel have the form of wedges or knives so as to offer less resistance and to cut and divide the gold bearing clay, cement etc. An opening of several feet in diameter is left 85 around the axis on both sides of the wheel for the purpose of feeding the inner part of the wheel with the gold bearing clay, cement etc. I place the gold isolating wheel or the gold-isolator on stationary supports, 90 like in the model, or I place it behind the wheels of a two wheel cart, by making the shafts behind as long as the radius of the gold-isolator may require and for the purpose of moving it to any place where it may 95 be desired.

Operation.—The water, in passing over the mining ground through a number of gutters or sluices receives the gold bearing clay, cement, etc. from the miner and carries 100 them by the force of its current to the gutter No. 1. Arriving at the perforations in the gutter No. 1 the water separates by passing through them into the lower gutter 105 No. 2 and from thereon the wheel. The wheel then being in motion, the miner introduces the gold bearing clay, cement etc. 110

which has remained on the perforated part of the gutter No. 1 over the two inclined gutters No. 3 and No. 4 into the inner part of the wheel or receiver. The only parts of the receiver with which the clay, cement, etc. comes in contact, are the arms of the wheel, the cover of the two sides, the door and the perforated metal. The clay, cement etc. fall on the perforated metal represented in the section by the line *a b c* and in the model by a piece of perforated metal covering about $\frac{1}{4}$ of the inner surface. In consequence of the rotary or circular motion and the friction with the inner parts of the wheel, the clay, cement, etc. are reduced to mud and pass with the gold through the openings out of the wheel into ordinary sluices, where the mud and sand pass off and the gold remains. By the velocity of the wheel as well as through the opening around the center the quantity of stones or fragments in the wheel can be ascertained and, when necessary, are discharged through the door in the periphery of the wheel and removed and treated in the same way as coarse gravel mixed with stones and containing fine or coarse gold or both. It may be stated here, that if there is a scarcity of water, say one inch only, a quantity insufficient for any mining operation, that a box with water may be placed below the wheel and large enough to keep the lower part of the wheel under water. If the wheel is then set in motion by some other power, the result will be the same, that is to say: mud, clean pieces of rocks and whatever gold there may be. One inch of water will then be used with advantage to wash the gold out from material of such light consistency and aggregation. Taking 20 inches of water for one sluice head at 2 dollars per day, the expense of one horse power will be less in many cases. But even 20 inches of water are of no use for such material, for which the machine of the applicant is intended unless one cubic foot of gold bearing matter contains more than 4 cents of gold.

Advantages.—The following facts will show the advantages resulting from the use of my gold-isolator. It is a known fact that most of the gold deposits are worked over a second and third time and that they pay sometimes better than the first time. The cause of which is that particles of gold have been kept inclosed in pieces of clay, cement etc. and that such have been thrown out by the sluicer or carried off by the current of the water and formed the tailings. The exposure to the air and water isolating the constituent parts of the clay cement etc. produces partly or wholly the principal condition for successful gold mining, viz: the separation or isolation of the constituent parts of the gold bearing matter. It is fur-

ther known that in many cases, where clay, cement or other tenacious earthy matter are predominating, only a small quantity can be worked in one day and that such material is exposed to the air, or dried, burned and stamped for the purpose of isolating the gold.

By the use of this gold-isolator there is: First, a complete isolation of the gold from all other matter. Second, no gold deposit will have to be worked over a second time. Third, a large quantity of clay cement etc. can be worked, which at present can not be done; either because the means of reduction are too expensive like drying, burning, and stamping, or they effect only a partial reduction and on a small quantity. A gold-isolator erected by the applicant for his private use in Dotys Flat, Placer county, California, is about $7\frac{1}{2}$ feet in diameter and 2 feet wide. With less than 10 inches of water and a fall of about 10 feet it reduces 1 cubic foot of hard clay in 2 minutes. In the manner of working, as used at present, only about 83 cubic feet of the same material could be worked in 10 hours and using 20 inches of water. By using 20 inches of water on the gold-isolator the result would be 600 cubic feet in 10 hours. Fourth, poor deposits can be worked because a large quantity of gold bearing matter can be reduced. Fifth, whereas the same amount of water will reduce a larger quantity, the charges for it will be less in proportion. Sixth, there is a large saving of labor, because the gold-isolator does all the work of reduction and no deposit will have to be worked over a second time. Seventh, gold mining can be carried on in flats and plains, where there is no fall for the water as used at present, and in such high places where a small quantity of water can be got only; because the gold-isolator can be set in motion by some other power and a few inches of water can be pumped. One horse power will effect as much as 100 inches of water costing 10 dollars per day and by using it in the manner it is done at present in the process of sluicing the gold bearing deposits.

I claim—

The combination of a water wheel with a separating or reducing machine into one apparatus by using the inner space of a wheel, partly or wholly inclosed, as a receiver, dispensing in this manner with couplings or connections and with a second vessel or receiver which would have to be set in motion by the water wheel, substantially as and for the purpose described.
